UNITED STATES PATENT OFFICE

ERNEST A. NORMAND, OF SAN FRANCISCO, CALIFORNIA

FREIGHT HOOK

Application filed July 23, 1930. Serial No. 470,013.

My invention relates to hand hooks for handling packages of freight, and particularly to a device having a spatulate hook.

An object of my invention is to provide a hook that will not injure paperboard cartons.

Another object is to provide such spatulate hook adapted to be held directly in the hand.

10 The invention possesses other objects and features of advantage, some of which, with the foregoing, will be set forth in the following description of my invention. It is to be understood that I do not limit myself to this disclosure of species of my invention, as I 15 may adopt variant embodiments thereof within the scope of the claims.

Referring to the drawings:

Figure 1 is a longitudinal elevation of the 20 hook of my invention, having a portion of the spatulate member cut away, as indicated by the line 1—1 of Figure 2.

Figure 2 is a front elevation of the spatulate engaging member alone.

25 Figure 3 is a perspective fragmentary detail view showing the preferred manner of forming the engaging edge.

Figure 4 is a perspective fragmentary detail view showing an alternative form of 30 engaging edge.

Figure 5 is a view of the spatulate engaging member being held directly in the hand.

In terms of broad inclusion my invention 35 comprises a comparatively wide spatulate freight hook having a plurality of short teeth along its engaging edge. A guard flange is provided along the edge of the hook in line with the bases of the teeth to prevent the hook from penetrating a fragile package such as a paperboard carton. While such a hook may be formed integrally in the same general shape as the ordinary pointed freight hook, I prefer to make the spatulate hook a 40 separate member adapted to be removably assembled on an ordinary hook so that a stevedore will not have to carry two handles. A further advantage resides in the separate hook construction, in that it permits the hook 45 to be used directly in the hand which elimi-

nates the necessity of the stevedore working with his arm in a bent position.

In terms of greater detail the hook of my invention comprises a plate formed into a curved spatulate engaging hook 2 preferably made of a mild sheet steel and having the teeth 3 disposed at intervals along its edge to engage the freight or package to be handled.

To insure that the teeth will not sink too 60 far into the package a transverse guard flange 4 is provided along the edge of the hook in line with the bases of the teeth. This flange is preferably formed as shown in Figure 3 by having the teeth punched out of the 65 flange as the latter is bent back. This requires a relatively expensive die, however, and an almost equally satisfactory structure can be obtained by slotting the edge and bending back the portions 6 to form a discontinuous flange as shown in Figure 4, while 70 other portions are sharpened to form the teeth as before. This latter construction is less expensive if the hooks are manufactured in small quantities.

75 The spatulate hook of my invention is preferably adapted to be removably attached to an ordinary freight hook, such as that shown in Figure 1, which comprises a curved hook 7, an intermediate curved shank 8, and a transverse handgrip 9 fixed thereon.

Suitable means are provided for holding the spatulate hook 2 on the curved hook 7. In the preferred form shown, this means comprises a loop 11 fixed on the hook 2 and disposed to engage the hook 7 adjacent its point; and a split sleeve 12 fixed on the hook 2 and adapted to engage the hook 7 adjacent the shank 8. The loop 11 may be a separate piece welded or otherwise fixed onto the main body of the hook 2, or it may be a raised or deformed portion if the hook is pressed or stamped out in a well known manner. The sleeve 12 can be formed integrally with the hook 2, or it can be made separately and welded or otherwise fixed on the hook 2. In general, however, it is less expensive to form the sleeve integrally with hook 2 as the labor of attaching a separate sleeve costs more than the material thus saved.

It will be noted that the hook 2 is rigidly constrained on the hook 7 by the loop and the sleeve because of the curvature of the hooks. Looking first at Figure 1 it is obviously impossible to move the hook 2 relative to the hook 7 in any direction lying in the plane of the paper except downward to slip the loop and sleeve along the hook 7. Unintentional movement in this direction is prevented by the resilient grip exerted by the sleeve 12 on the hook; and movement in the opposite direction is limited by the dimension of the loop 11. Similarly on referring to Figure 2 it can be seen that it would be impossible to rotate the hook 2 in either direction in the plane of the paper if the sleeve 12 and loop 11 were fixed in position.

When handling relatively small packages it is somewhat easier for the stevedore to work with his arm in a straight or nearly straight position than it is to work with his arm bent or drawn in as it will be if he is using the ordinary hook. It is to shorten the reach and thus lighten the work that provision is made to use the spatulate hook directly in the hand, as shown in Figure 5.

To facilitate such employment the depressions 13 are preferably formed in the surface of the hook 2 to offer an engaging surface to the finger tips. The back end 14 of the sleeve 12 is suitably rounded off so that it will not injure the palm of the hand; and a strap 16 is inserted in a suitable loop 17 provided on the under side of sleeve 12 and is buckled about the hand. The depressions 13 are desirable for steadiness, but are not essential as the force is outward against the finger tips and there is little tendency for the hook to slip. It will be noted also that the force exerted when the hook engages a package tends to pull the sleeve 12 away from the palm of the hand so that there is no particular discomfort caused by that member. I have found that the strap shown is the most convenient method of holding the hook on the hand since it can be removed and carried in the pocket comfortably and is not in the way when the hook 2 is used in conjunction with an ordinary freight hook.

I have found that the use of this hook of my invention reduces freight handling costs by speeding up the handling of paperboard and burlap wrapped packages, and that costs are further reduced by the decreased damage done the contents of such packages. This latter saving follows from the fact that the flange protected teeth on the hook of my invention cannot penetrate deeply into a package; and further, that less packages will be dropped if such a hook is used instead of the bare hands alone.

I claim:

1. A spatulate freight hook comprising a plate having teeth along an edge thereof, and a transverse flange comprising a portion of

the plate bent outwardly adjacent the base of the teeth.

2. A spatulate freight hook comprising a plate having teeth along an edge thereof, and a discontinuous transverse flange fixed along the edge of the plate adjacent the base of the teeth. 70

3. A spatulate freight hook comprising a plate having teeth along an edge thereof, a transverse flange fixed along the edge of the plate adjacent the base of the teeth, and means for removably attaching the plate to a human hand. 75

4. A spatulate freight hook comprising a plate having teeth along an edge thereof, a transverse flange fixed along the edge of the plate adjacent the base of the teeth, and resilient loops on the plate for removably attaching the plate to an ordinary freight hook. 80

5. A spatulate freight hook comprising a plate having teeth along an edge thereof, and means for removably attaching the plate to a human hand, said plate extending beyond the ends of the fingers. 85

6. A spatulate freight hook comprising a plate having teeth along an edge thereof, means on the plate providing for its attachment to a human hand, and means on the plate providing for its attachment to an ordinary freight hook. 90

7. A spatulate freight hook comprising a plate having teeth along an edge thereof, a transverse flange fixed along the edge of the plate adjacent the base of the teeth, means on the plate providing for its attachment to a human hand, and means on the plate providing for its attachment to an ordinary freight hook. 95

8. A spatulate freight hook comprising a plate having teeth along an edge thereof, and a loop adapted to receive a hand strap fixed adjacent the opposite edge thereof. 105

9. A spatulate freight hook comprising a plate having teeth along an edge thereof, a transverse flange fixed along the edge of the plate adjacent the base of the teeth, a loop fixed on a face of the plate to receive the point of an ordinary freight hook, a sleeve fixed adjacent an edge of the plate opposite the teeth to receive said ordinary freight hook, and a second loop adapted to receive a hand strap fixed on the sleeve. 110

In testimony whereof, I have hereunto set my hand.

ERNEST A. NORMAND. 120
